UNITED STATES PATENT OFFICE.

HARRY Y. HALL, OF SAN FRANCISCO, CALIFORNIA.

ELECTRIC BOOSTER SYSTEM.

1,324,348.

Specification of Letters Patent.

Patented Dec. 9, 1919.

Application filed April 24, 1916. Serial No. 93,062.

To all whom it may concern:

Be it known that I, HARRY Y. HALL, a citizen of the United States, and a resident of the city and county of San Francisco,

5 State of California, have invented a certain new and useful Electric Booster System, of which the following is a specification.

The invention relates to electric booster systems for use particularly in limiting 10 track drops and potential differences in electric railway and other electric circuits.

An object of the invention is to provide means for automatically controlling track drops and potential differences in track 15 return or other return electric circuits.

Another object of the invention is to provide means for overcoming the limitations of the ordinary series booster system.

Another object of the invention is to provide 20 a booster system which operates to hold the difference in potential between two distantly spaced points on the rail or feeder at a lower value than is possible with systems heretofore used.

25 The invention possesses other advantageous features, some of which, with the foregoing, will be set forth at length in the following description, where I shall outline in full that form of the invention which I have selected for illustration in the drawing accompanying and forming part of the present specification. In said drawing I have shown one specific form of my generic invention, but it is to be understood that I do 30 not limit myself to such form, because the invention as expressed in the succeeding claims may be embodied in a multiplicity of forms.

The drawing is a diagrammatic representation 40 of one form of the system of my invention.

To limit the liability to electrolysis of water and gas pipes, regulations have been adopted in many communities which restrict 45 the potential drop in the track-return circuit of electric railways to a certain maximum, and these regulations are complied with by the installation of heavy track-return feeders and track-return boosters. These booster 50 systems have usually been of the ordinary series booster type, which systems have certain inherent short-comings and limitations, which render them unsuitable for conditions of operation wherein a very low potential 55 difference is required between two distantly spaced points on the feeder or rail.

Under varying conditions of traffic, and without the use of a booster system, the difference in potential between two distantly spaced points on the rail varies to a great 60 extent and when a booster system is employed, the booster voltage should vary equally and oppositely in the same degree, so that the difference in potential is maintained below a certain maximum. This requires a booster having a wide range of voltage regulation, from zero to maximum and for this purpose I employ a separately excited booster. In many instances it is impossible to obtain the desired voltage variation with the use of a single exciter with sufficient rapidity and stability to meet the demands of many conditions. In accordance 65 with my invention, I prefer to employ a booster and two excitors of different normal voltages, connected in opposition so that the resultant voltage is the voltage impressed upon the booster field winding. The low voltage exciter preferably operates at a constant voltage and the higher voltage 70 exciter, which is connected in opposition, operates at a variable voltage, which is controlled by a voltage regulator.

In the drawing, the rail or feeder 2 is shown as running from a point A to a distant point B, and the booster feeder 3, containing the suitably driven shunt wound, separately excited, booster or generator 4, is connected to the rail or feeder 2 at these two points. The booster field 5 is supplied 75 by the two excitors 6 and 7 connected in opposition, so that the field voltage is equal to the difference in voltage of the two excitors. The normal booster voltage is equal to the difference between the normal voltages of 80 the excitors. The exciter 6, which is the low voltage exciter, operates at a substantially constant voltage and may be a generator, a battery or some other source of substantially continuous voltage. The exciter 7 is the 85 higher voltage exciter and operates at a variable voltage. Since the two excitors are connected in opposition, when their voltages are the same, the resultant is zero voltage and no current flows into the booster field, 90 but when the variable voltage is higher than the constant voltage, current flows into the booster field, causing the generation of voltage in the booster armature which draws the return current back to the sub-station 95 through the booster feeder 3 instead of through the negative feeder or rail 2. The 100 105 110

voltage of the booster and the size of the booster feeder are so chosen, that when the booster is drawing the total return current through the booster feeder, the drop therein and the booster voltage are substantially equal and opposite, resulting in practically no difference of potential between the points A and B on the feeder or rail.

The voltage of the variable voltage exciter 7 is regulated by a suitable regulator, such as the Tirrill regulator 8 which is arranged adjacent the exciter and in the circuit of the control wire 9, connected to the rail 2 at the two points A and B. The Tirrill regulator shown is of slightly modified form, so that it regulates for and to hold practically zero volts instead of a definite voltage, as ordinarily. To accomplish this result, the control element of the regulator is formed of two coils 12 and 13, the coil 12 being connected across the constant voltage exciter 6 and the coil 13, which is the true control coil, is connected in series in the control wire 9. The pull of these two coils will be in the same or in opposite directions, depending upon whether point B is at a lower or a higher potential than point A.

In one booster and regulator system which I have designed, in which opposed excitors are used, I have provided a separately excited 125 volt shunt booster and have provided a constant voltage 125 volt exciter and a variable voltage exciter connected in opposition thereto having a maximum voltage of 250 volts. By varying the voltage of the second exciter between 125 volts and 250 volts, the voltage of the booster field is varied from zero to 125 volts, and by this arrangement, this range of voltage is obtained with greater rapidity and stability than would be possible with a single 125 volt exciter whose voltage must be varied from zero to 125 volts.

I claim:

1. In an electric booster system, a separately excited booster having a field winding, an exciter connected across said winding, a conductor to which said booster is connected at distantly spaced points and means operative by variations in the potential difference of said two points for varying the exciter voltage.

2. The combination with an electric conductor, of a booster circuit connected there-

to at two distantly spaced points, a booster in said circuit having a field winding, an exciter connected across said winding, a control wire connecting said spaced points and a regulator in the control wire circuit connected to said exciter and adapted to control the voltage thereof.

3. The combination with a track-return conductor of a booster circuit connected thereto at distantly spaced points, a booster in said circuit having a field winding, two excitors connected in opposition and supplying said field winding and means operative by variations in the potential difference of said two points for varying the voltage of one of said excitors.

4. The combination with an electric conductor, of a booster circuit connected thereto at two distantly spaced points, a booster in said circuit having a field winding, two excitors of different normal voltage connected in opposition connected across said winding, the lower voltage exciter having a substantially constant voltage and means operative by variations in the potential difference between said spaced points for varying the voltage of the higher potential exciter.

5. The combination with an electric conductor, of a booster circuit connected thereto at two distantly spaced points, a booster in said circuit having a field winding, two excitors of different normal voltage connected in opposition connected across said winding, the lower voltage exciter having a substantially constant voltage, a control wire connecting said spaced points and a regulator in the control wire circuit connected in series with the field of the higher voltage exciter whereby variations in the potential difference between said spaced points varies the voltage of said higher voltage exciter.

6. The combination with an electric conductor, of a booster circuit connected thereto at two distantly spaced points, a booster in said circuit and means for automatically varying the potential of the booster whereby the voltages at said two points are maintained substantially equal.

In testimony whereof, I have hereunto set my hand at San Francisco, California, this 15th day of April, 1916.

HARRY Y. HALL.
